UNITED STATES PATENT OFFICE.

JOHN ROWLAND TORRANCE, OF BITTON, ENGLAND.

DISK AND LIKE GRINDING MILL.

1,405,878.

Specification of Letters Patent. Patented Feb. 7, 1922.

Application filed July 7, 1919. Serial No. 309,188.

To all whom it may concern:

Be it known that I, JOHN ROWLAND TORRANCE, a subject of the King of Great Britain, residing at Bitton, England, have invented certain new and useful Improvements in and Relating to Disk and like Grinding Mills, of which the following is a specification.

The present invention is for improvements in and relating to disk and like grinding mills, which can be suited or adapted to both dry grinding and to grinding fluids or mixtures which become fluid after grinding, particularly of the type of mill consisting of an upper perforate grinding organ which forms a receptacle for the material to be ground and the lower face of which forms a grinding surface; the other grinding surface being a rotating disk 20 which bears against the grinding surface of the receptacle.

Mills of this kind are known (see British specifications of the present applicant's patents numbered 14733/1912 and 25 13560/1913) in which the rotating and usually lower member is given a supplementary motion of nutation or wavering and scraper or sweeper is movable in synchronism with the nutating or wavering and rotating 30 grinding member.

The present invention is directed to a mill of the type in which the grinding members are two flat disks of stone, porcelain, metal or like, and in which the grinding members while held in the required proximity with each other grind one over the other with a compound relative rotary and lateral bodily movement.

In a flat stone mill of this type having 40 a rotating and usually lower member, it has been proposed to give to the rotating member a supplementary motion to cause it to move bodily over its companion member with a continual change of position, by 45 imparting to the running stone an orbital or planetary motion so that instead of running in true concentricity with its companion stone it is moving in and out in a progressive manner in relation to the margin of its companion stone.

In practice in order to produce ground material of high quality a slow lateral or orbital or planetary motion of the running member is desirable in relation to the rota-

tory motion, for, otherwise the outfeed of 55 the material is too rapid, and further there is subversive vibration. Amongst the objects of the present invention is the overcoming or minimizing of the defects above set forth by the provision of a mill where- 60 in a high velocity ratio between the rotatory drive and the lateral bodily drive, each driven from a common main shaft is ef- fected, by intermediate worm gearing as the bodily drive, whereby a compact, smooth 65 running, and notably fine grinding mill is made possible. Under an exemplar form of the invention gearing is introduced between the counter shaft carrying the worm gear- 70 ing and the main drive by which the ve- locity ratio between the rotatory drive and the lateral bodily drive may be varied up or down as desired without changing the worm gearing.

To the above and other ends and by way 75 of example, I will describe a form of flat-stone mill which works well, in which the compound rotatory and lateral bodily move- ment of the running stone is imparted by means of a shaft in a rotating eccentric 80 sleeve.

In the accompanying drawings is illus- trated in detail and by way of example an application of the invention to a paint mill, in which mill by actual test, the following 85 speeds have been found suitable:

Driving shaft 255 revolutions a minute.

Rotatory speed of stone 85 revolutions a minute.

Velocity ratio between drive and rotatory 90 speed 3 to 1 reduction.

Velocity ratio between drive and lateral bodily drive 38 to 1 reduction.

Velocity ratio between rotatory speed and lateral bodily drive 12.6 reduction. 95

In the drawings:—

Fig. 1 is a sectional elevation of a mill constructed in accordance with the present invention. Fig. 2 is a side view thereof looking from right to left of Fig. 1. 100

Fig. 3 is a plan section to an enlarged scale of the main bearing, eccentric bush, and rotating shaft of the grinding member.

Fig. 4 is a sectional elevation showing one form of drive for the rotating shaft of the 105 grinding member, also the rocking footstep bearing for the rotating shaft and the grinding pressure adjusting arm or lever.

Fig. 5 shows an alternate form of drive for the rotating shaft of the grinding member.

Fig. 6 is a plan of the grinding pressure adjusting arm or lever.

Fig. 7 is a plan view of the drive illustrated in Fig. 4, and Fig. 8 a plan view of the drive shown in Fig. 5.

Figs. 9 and 10 illustrate a form of scraper which may be used when the mill is suited or adapted for grinding fluids, while Figs. 11 and 12 are elevation and plan respectively of a revolving scraper which may be used in lieu of the aforesaid scraper or for dry 15 grinding.

Fig. 13 is a view of a form of worm drive for imparting the lateral bodily drive to the running member.

As illustrated the mill comprises two 20 grinding members or disks *a* and *b* of stone, porcelain, metal or the like, the upper disk *a* of which is stationary. This upper disk *a* is fixed to a cover plate *c* carrying a hopper *d* through which the material to be ground 25 passes to the grinding surfaces.

The lower disk *b* is fixedly carried by a 30 rotating shaft *e* mounted in a rotating eccentric bush or sleeve *f*, this bush or sleeve being mounted and running concentrically 35 in a main neck bearing *g* forming a fixed part of the lower casing *h* of the grinding members. A compound rotary and lateral bodily movement of the lower disk *b* is effected by fixing the same to rotate with 40 the shaft *e*, which shaft is mounted in the rotating eccentric bush *f* mounted and running concentrically in the main bearing *g* whereby the axis of the disk *b* is caused to 45 generate a cylinder about the produced normal axis of the companion grinding member *a*, and there is realized a combined lateral and circular grinding action with a progressive moving in and out of the rotating grinding member *b* in relation to the stationary grinding member *a*. The means 50 for imparting this compound rotary and lateral bodily movement is hereinafter referred to.

The lower end of the shaft *e* is rotatably 55 mounted in the upper end of a rocking footstep bearing *i* to allow for the throw of the eccentric. A ball thrust bearing *j* for receiving the shaft *e* is provided at the top end of the pillar of the footstep bearing. 60 The footstep bearing *i* is supported so as to be capable of adjustment for height to vary the grinding pressure. As shown, the bearing is carried in a socket *j'* by a pivoted arm *k* adapted to be raised or lowered by a screw adjustment *l* bearing in a bracket *m* on the frame *n* of the mill.

A main driving shaft *o* having fast and loose pulleys *p*, *p'* is borne in standards *r* on the frame *n*. Drive of the eccentric bush 65 or sleeve *f* is by a worm *s* and worm wheel

t. The worm *s* is on a shaft *u* borne by a bearing *w* depending from a ring *x* fixed upon the outside of the main neck bearing *g*, and the worm wheel *t* is on the eccentric bush or sleeve *f*. The worm shaft is driven 70 from the main driving shaft *o* by means of spur wheels *y*, *y*. By changing the spur wheels the power of varying the velocity ratio up or down between the sleeve and the shaft may be effected.

The drive of the shaft *e* of the grinding member *b* is by a bevel gear from the main driving shaft. Referring to Figs. 5 and 8 a bevel wheel *1* is rotatably mounted on the eccentric bush *f* and is driven by a bevel 80 wheel *2* on the main driving shaft *o*. The bevel wheel *1* carries a depending tubular piece *3* in which are radial grooves *4* within which co-operate projections *5* fixed on the lower end of the shaft *e* of the grinding 85 member *b*.

The width of these projections *5* and grooves *4* are so relatively proportioned that the continuous hypotrochoidal or similar motion of the shaft is allowed for, and the 90 drive taken up by each horn in sequence.

In the alternative form of drive as illustrated by Figs. 4 and 7 the depending tubular piece *3* is formed or provided with an internally toothed ring *6* adapted to engage 95 a pinion *7* formed or provided on the lower end of the shaft *e* of the grinding member *b*.

When the mill is suited or adapted for 100 grinding fluids, a scraper or "doctor" is provided for cleaning the edge of the grinding member *b*. As shown in Figs. 9 and 10 the scraper *8* is carried in a fitting *8^a* on an arm *9* which extends from a ring or bush *10* loosely mounted on the neck of the eccentric bush or sleeve *f*. The arm passes 105 through a guide *11* and moves in synchronism with the lateral bodily movement of the rotating grinding member *b*. A scraper or "doctor" may also be used when grinding 110 dry material.

For giving the desired yielding pressure of the scraper on the grinding member, an adjustment of the fitting *8^a* is provided for by means of a screw *8^b* with interposed 115 spring *8^c*.

In Figs. 11 and 12 is shown an alternative form of scraper or "doctor." In this arrangement the arm *9* is fast with the neck of the eccentric bush or sleeve *f* so as to revolve therewith. The arm has connected 120 thereto a scraper *12* and a sweeper *13* for keeping the annulus *14* clean, thus operating to sweep any droppings to the delivery outlet, as well as to clean the outer edge of the grinding member *b*. A scraper or "doctor" 125 may also be used when grinding dry materials.

For grinding mixtures comprising a volatile component the feeding hopper is covered in, and a sliding door *14^a* and de- 130

livery chute 15 is provided in the casing *h* which encloses the grinding members.

A stirrer or sweeper 16 may when desired be provided on the hopper *d*, the 5 sweeper being coupled to the upper end of the shaft *e* and revolved therewith.

Whilst the disk members have been described as being superimposed, they may be arranged on their sides, in which case the 10 drive would be suitably varied to suit requirements.

The grinding disks may be so arranged that means can be embodied therein, for example, by a water circulatory system, for 15 cooling purposes.

The companion stone in some cases may be caused simultaneously to change position, for example, by a slow horizontal motion or motion in the plane of the stone in 20 two directions at right angles.

What I claim is:—

1. A drive for a grinding mill of the type described having in combination a common main shaft, means for imparting a rotary 25 drive to the grinding disk carrying shaft mounted in the rotating eccentric bush, said means comprising a bevel gear, the driven bevel of which is rotatably mounted on the eccentric bush, a tubular piece carried by 30 said driven bevel, radial slots in said tubular piece, projections fixed on the lower end of the disk carrying shaft, said projections co-operating with the radial slots in the tubular piece, and means comprising worm gearing 35 for imparting the bodily drive to the grinding disk, said latter means being also driven from said common main shaft.

2. A drive for a grinding mill of the

type described having in combination a common main shaft, means for imparting a 40 rotatory drive to the grinding disk carrying shaft mounted in the rotating eccentric bush, said means comprising a bevel gear, the driven bevel of which is rotatably mounted on the eccentric bush, a tubular piece carried by 45 said driven bevel, radial slots in said tubular piece, projections fixed on the lower end of the disk carrying shaft, said projections co-operating with the radial slots in the tubular piece, a counter shaft, 50 means comprising worm gearing carried by said counter shaft for imparting the bodily drive to the grinding disk, and gearing introduced between the main shaft and the counter shaft for the purpose set forth. 55

3. A drive for a grinding mill of the kind described having in combination a common main shaft, means for imparting a rotatory drive to the grinding disk carrying shaft mounted in the rotating eccentric bush, said 60 means comprising a bevel gear, the driven bevel of which is rotatably mounted on the eccentric bush, a tubular piece for drive transmission from said driven bevel, co-operating connecting radial slots and projections between said tubular piece and the lower end of said disk carrying shaft, a counter shaft, means comprising worm gearing carried by said counter shaft for imparting the bodily drive to the grinding 65 disk and gearing introduced between the main shaft and the counter shaft for the purpose set forth. 70

In testimony whereof, I affix my signature.

JOHN ROWLAND TORRANCE.
